Inventor
Martinius Joannes Stam
By D. Singer, atty.

UNITED STATES PATENT OFFICE.

MARTINUS JOÄNNES STAM, OF THE HAGUE, NETHERLANDS.

POLE FOOTING.

Application filed October 11, 1926, Serial No. 140,960, and in the Netherlands October 13, 1925.

My present invention relates to a pole-
footing for wooden or other poles or piles,
used for supporting electricity, telephone,
telegraph and such lines, in short poles
5 which must be partly dug into the earth in
order to acquire the necessary stability, and
which are made of a material, which is liable
to rot or rust or is somehow destroyed by its
contact with damp earth.

10 The pole-fooing may be made of concrete,
either reinforced or not, or a similar material
which resists the influence of damp earth.

According to my present invention the
15 pole-fooing is made of two parts or two
halves. The known constructions of this
kind present the difficulty, that both parts
of the footing are attached to the pole by
means of one or several bolts, running
20 through the latter; the holes made in the
wood are a ready cause of rotting or de-
cay of the material of the pole. A marked
disadvantage of these constructions is that
the two parts of the footing must be con-
25 nected with each other by means of three
bolts or braces, viz. one through or round
the middle of the footing and one at each
end thereof. This arrangement is faulty
because the poles—especially the wooden
30 ones, which are thinner at the top than at
the bottom—never have the same shape,
hence by tightening the intermediate bolt,
either the top or the lower of the two other
bolts can no longer keep the parts tightly
35 assembled.

This drawback is entirely avoided by ap-
plication of the invention.

The pole-fooing according to my inven-
tion consists of two entirely similar parts,
40 having a rounded shape, the curvature of
which is however stronger than that of the
pole. Each pole is therefore perfectly sup-
ported at four different places. The parts
are provided with inner projections, through
45 which, and under the pole, the bolt passes.
Hence the latter needs not to run through
the wood nor is it in contact with the earth.
This bolt acts as a rotation centre when the
bottom ends of the footing are pushed apart
50 by means of a stud bolt with nuts. In this

way both parts of the footing are firmly
clamped round the pole.

This pushing apart of the bottom ends of
the footing may be done in different ways,
as e. g. by means of a key driven between 55
the parts.

In the accompanying drawing:

Figure 1 illustrates a vertical section;

Figure 2 a side elevation view;

Figure 3 a horizontal section on the line 60
3—3 of Figure 1 and in plan disclosing the
bolt 2;

Figure 4 an end view and

Figures 5 and 6 show views of the bolts
2 and 3. 65

Figure 7 is a detail sectional view of the
lower portion of the footing, showing in ele-
vation a key connecting and arranged for ad-
justing or pushing apart the bottom ends of
the footing, according to a modification of 70
the invention.

The footing consists of the parts 1, 1, a
bolt 2, a stud bolt or key 3, hence four parts
in total.

The inner projections 4, whereupon the 75
base of the pole rests, may have an inclined
upper face, in order to allow the water run-
ning down the pole to escape. Existing
poles can also easily be fitted with the foot-
ing according to the invention and by so 80
doing their life is considerably lengthened.

In Figure 7 is illustrated a modification of
the invention in which a wedge shaped key
5 is employed as connecting means between
the lower ends of the members 1^a, which 85
members are provided on their opposing
sides with downwardly converging inclined
surfaces 6 against which the correspond-
ingly shaped sides of the key bear. 90

What I claim, is:

1. A pole footing of the class described
comprising a pair of members provided in
their opposing sides at their upper ends
with recesses to receive the lower end of a
pole between them, means connecting said 95
members together for angular movement of
said members, said connecting means being
intermediate the ends of said members and
means connecting the lower ends of said
members together, said connecting means 100

being arranged for adjusting said members so that their lower ends may be forced apart to cause the pole to be firmly gripped between the upper ends of said members.

5. 2. A pole footing as claimed in claim 1 in which the first named connecting means is a bolt loosely fitted in openings with which said members are provided and the

second named connecting means is also a bolt fitted in openings near the lower ends of 10 said members and provided with adjusting nuts which bear against the opposing sides of said members.

In testimony whereof, I have signed my name to this specification.

MARTINUS JOANNES STAM.
